UNITED STATES PATENT OFFICE.

LEON LEVY, OF NEW YORK, N. Y.

THEATRICAL DEVICE.

Application filed December 30, 1921, Serial No. 525,983. Renewed January 9, 1924.

To all whom it may concern:

Be it known that I, LEON LEVY, a citizen of the United States, residing at New York, in the county of New York and State of New York, have invented certain new and useful Improvements in Theatrical Devices; and I hereby declare that the following is a full, clear, and exact description thereof, reference being had to the accompanying 10 drawings, which form part of this specification.

My invention is a theatrical device for the amusement of audiences, an object being to seemingly project a person through a solid. 15 Another object is to construct a device so simple in appearance that it may be inspected without disclosing its operative parts. Still another object is to construct my device with a minimum number of 20 parts.

In the construction of my invention I have found it most desirable to use wood and steel but it will be understood that I do not restrict myself to these metals or 25 materials or to the exact form herein set forth.

Referring to the drawings: Fig. 1, denotes an elevation of my invention, partly broken away. Fig. 2, is a side elevation of 30 Fig. 1. Fig. 3, is a side elevation in cross section showing the cannon support in a raised position. Fig. 4, is a like view, showing the cannon support in the lowered position with the cannon attached. Fig. 5, 35 is an enlarged segment of the cross section of the cannon support shown in Fig. 3. Figs. 6 and 7 denote means by which dummy cannon support is attached to the main frame. Fig. 8 is an enlarged section 40 through 8—8 Fig. 1. Fig. 9, is an elevation showing the back of the cannon support. Figs. 10, 11 and 12 denote views of any 45 cannon which may be employed in connection with my invention.

Referring more particularly to the drawings:—1, denotes a double faced frame or moulding between the uprights of which are positioned counter weight boxes 2 for the reception of counter weights 3 having attached thereto sash cords 4 which pass over pulleys 5 positioned near the top of the frame. The other end of the sash cords are securely fastened in recesses 6 formed in a steel or other solid plate 7 which slides like 50 the sash in a window frame. The edge of this plate rests against the respective sides

of the counter weight boxes 2. This plate 7 has a hole 8 positioned out of center therein for a purpose to be hereafter set forth. This plate 7 slides between four plates of similar 60 material rigidly held in frame 1 and are denoted as follows; top front plate 9, bottom front plate 10, top back plate 11, bottom back plate 12. Four narrow strips of wood or other material 13 are horizontally disposed, two on the front and two on the back of frame 1 and are so positioned as to substantially divide said frame into three parts. These strips 13 cover the exposed 65 edges of plates 9, 10, 11 and 12, thereby giving the effect of one continuous sheet of steel positioned in frame 1. This effect remains the same regardless of the position of plate 7. The said strips 13 are also adapted for attaching thereto pieces of paper or 70 other pliable material, which will be hereafter described.

A bar which we will hereafter call the cannon support 14 is attached rigidly to solid plate 7 by means of bolts or studs 15, 80 positioning said support parallel to and substantially distant from said solid plate 7 thus allowing the upper portion of cannon support 14 when raised to pass over upper front strip 13. In the cannon support 14 is 85 an opening or hole 16 which is in continuous registration with hole 8 of the solid plate 7, that is to say these openings are always moved up and down together though it is apparent that at times the plate 9 is between 90 holes 16 and 8. This opening 16 is covered with rubber or other elastic material, slashed to form a star trap 17. A like opening 32 is formed in the dummy cannon support 25 to be more fully referred to in the latter 95 part of this specification. A flange 18 is formed around the star trap 17, projecting outwardly and forming a cannon muzzle housing.

In the back of the cannon support 14 is 100 formed a longitudinal recess forming a housing 19 to conceal two spring rollers 20 and 21 which are horizontally disposed therein. These rollers are similar to the ordinary sash rollers. Roller 20 carries a web or shade 105 of paper 50 or other pliable material, one edge of which is permanently tacked or otherwise securely fastened to the roller and the other edge fastened to upper front strip 13. In this paper is a hole 51 which registers with hole 8 and opening 16 when the 110 cannon support 14 is in the position shown

in Fig. 4. Roller 21 has attached thereto a short shade or web of cloth or other material 22, the outer edge of which is attached to a slat 23 in such a manner that only the slat is visible to the audience. This slat 23 extends the full length of the roller 21 so that its ends are concealed behind the cannon support 14 as shown in Fig. 1. A paper 24 which is not the length of slat 23 may be 10 attached to this slat the other edge of the paper being attached to lower front strip 13.

It is apparent that when cannon support 14 is lowered that steel plate 7, which is integral therewith through studs 15 is also 15 lowered. The lowering of the cannon support 14 causes roller 20 to unroll and roller 21 to roll up slat 23 and the paper 24 thereto attached. From the audience it appears that 20 paper 50 and the paper 24 are but one sheet of paper and that the cannon support 14 is being lowered over this single sheet of paper.

On the back of frame 1 is a dummy cannon support 25 which is removably attached 25 and may be secured to the frame 1 in positions corresponding to the raised and lowered positions of cannon support 14. The attaching means is shown in Figs. 6 and 7 key holes denoted by 26 and catches by 27. 30 The said dummy cannon support 25 is similar to cannon support 14 but does not contain rollers 20 and 21 nor the housing 19, otherwise it is similar in appearance and may be detached and passed to the audience 35 for examination.

In constructing my device the sliding or center plate 7 is highly polished so that its movement up and down is not apparent to the audience.

40 When the cannon support 14 is moved down the muzzle of cannon 28 is attached to flange 18 by hasps 30. As shown in Fig. 6 the muzzle of the cannon 28 the hole 51 in paper 50 the hole 8 in steel plate 7 and the 45 hole 32 in dummy cannon support 25 are in line. It will also be noted that the paper 29 is intact. It is this paper which is torn when a person is projected from the cannon 28 as explained hereafter. This paper 29 is 50 attached to the top and bottom strips or bars 13 on the back of frame 1.

The frame 1 is mounted in a stand denoted by 31.

55

Operation.

The dummy cannon support is positioned in the center of the frame, with the cannon attached thereto. The cannon is disconnected and moved away. The dummy support and 60 paper 29 are removed from the frame. The cannon support is in raised position.

Another sheet of paper 24 is now attached to the lower front strip and slat. The dummy support and first mentioned paper 65 are placed in position. The cannon support

is lowered unrolling paper 50 and rolling paper 24.

The person, animal or other projectile is now projected by means of springs, air or other pressure, breaking paper 29.

Claims:

1. In a theatrical device, the combination of a stand; a two-faced frame mounted on said stand; two counterweight boxes positioned in the sides of said frame; counterweights operating in said boxes; a slidable plate mounted in said frame and provided with an eccentric hole; cords connecting said sliding plate with said weights; two plates rigidly mounted in each side of said frame adapted to conceal the upper and lower portions of said sliding plate respectively; a bar or cannon support rigidly attached to said sliding plate and provided with a hole registering with the hole in said sliding plate, and a star trap adapted to conceal said holes; two rollers horizontally mounted in said bar or cannon support; two strips rigidly positioned horizontally across each face of said frame; two flexible webs adapted for attachment to two of said strips and said rollers on one side of said frame; a third web adapted to be attached between the other two strips on the other side of said frame; and a dummy bar or cannon support detachably mounted on the back of said frame and provided with a hole suitable for registration with the holes in said sliding plate and said cannon support, and a star trap adapted to conceal said holes. 100

2. In a theatrical device, an upstanding frame; a plate provided with a hole and adapted to slide in said frame; a bar or cannon support provided with a hole, fixed to one side of said plate; a second bar or cannon support adjacent the opposite side of said plate, detachably mounted upon said frame and having therein a hole adapted to register with the holes in said plate and said first support; and means for hiding the hole 110 in said plate. 105

3. In a theatrical device, an upright frame; a sliding plate provided with a hole, and adapted to slide in said frame; two plates rigidly mounted in each side of said frame adapted to conceal the upper and lower portions of said sliding plate respectively and also adapted to conceal the hole in said sliding plate; a bar or cannon support provided with a hole, fixed to one side of said plate; a second bar or cannon support adjacent the opposite side of said plate, detachably mounted upon said frame and having therein a hole adapted to register with the holes in said sliding plate and said first support; and means for hiding said holes. 115 120

4. In a theatrical device, an upstanding frame; a plate provided with a hole and adapted to slide in said frame; a bar or 130

cannon support provided with a hole, fixed to one side of said plate; two rollers concealed in said support and adapted to roll and unroll alternately; two webs adapted 5 to appear as one web, provided to wind and unwind upon said rollers respectively; a second bar or cannon support adjacent the opposite side of said plate, detachably mounted upon said frame and having there-
10 in a hole adapted to register with the holes in said sliding plate and said first support; and means for hiding said holes.

5. In a theatrical device, an upright

frame; a plate provided with a hole, adapted to slide in said frame; a bar or 15 cannon support provided with a hole, fixed to one side of said plate; a second bar or cannon support detachably mounted on the back of said frame and provided with a hole; star traps mounted in the holes of 20 said first and second supports and adapted to conceal the hole in said plate.

In testimony that I claim the foregoing as my own, I affix my signature.

LEON LEVY.
